EUGEN BURIAN, OF HLOHOVEC, CZECHOSLOVAKIA. ASSIGNOR TO NAAMLOOZE VEN-
NOOTSCHAP KONINKLIJKE STEARINE KAARSENFABRIEK "GOUDA," OF GOUDA,
NETHERLANDS.

PROCESS FOR THE MANUFACTURE OF CANDLES, TAPERS, AND THE LIKE AND TO AN
APPARATUS FOR CARRYING OUT SUCH PROCESS.

Application filed January 29, 1924. Serial No. 689,361.

To all whom it may concern:

Be it known that I, EUGEN BURIAN, a subject of the Czechoslovakian Republic, residing at Hlohovec, Czechoslovakia, have 5 invented certain new and useful Improvements in a Process for the Manufacture of Candles, Tapers, and the like, and to an Apparatus for Carrying Out Such Process, of which the following is a specification.

10 The present invention relates to a process for the manufacture of candles, tapers and the like and to an apparatus for carrying out such process.

It has been proposed already to manufacture tapers, by successively leading the wick 15 through a series of successively arranged wax baths, while the wick, after having passed through each bath is drawn through a die, the diameter of which is larger than 20 that of the preceding one, until the wick has attained the desired thickness. These known apparatus are, however, expensive and require much floor space. In contradistinction therewith, a considerable simplification and a great saving in space are 25 obtained by the process and the apparatus according to this invention.

In my process, the wick is led through 30 a bath of wax, paraffine, stearine or the like or mixtures of these materials, and is subsequently drawn through a die, which, every time after the wick has travelled over its entire length, without loosening the wick, is replaced by or varied into a die of a larger 35 diameter. The replacing or variation of the dies is continued until the desired candle-thickness has been attained.

According to the invention very good results are obtained, by carrying out the process, by means of an apparatus, in which the wick, in the shape of an endless band, by means of a set of drums, is led through the bath and is subsequently drawn through a die, which, during the working, can be 45 replaced by or varied into a die of a larger diameter, without loosening the wick. In this manner the process can be worked continuously, and with the aid of only one bath.

According to the invention the interchanging or the variation of the die can be effected in different ways, for instance the die can be made in two or more parts, which 50 parts may be fastened in tongs or a clamping

device, that can be easily loosened or opened. It is also possible to arrange a plurality of 55 dies of increasing diameters, in successive order, in such a manner, that each separate die can successively be put into or out of operation.

The accompanying drawing illustrates, by 60 way of example, one of the simplest forms of execution of an apparatus for carrying out the process according to this invention.

In this drawing

Fig. 1 is a side-elevation,

Fig. 2 a plan view, and

Fig. 3 a back-view of the apparatus, while in

Figs. 4 and 5 details of the apparatus are 10 illustrated on a larger scale.

On the drums 1, 2 and 3, rotatable on ball-bearings, a wick 4, in the shape of an endless band, is wound in such a manner, that it lays on the drums 2 and 3 in a number of windings, in order to produce in one 75 single working-operation, candle-material of the greatest possible length. That part of the wick, which forms the connection between the last winding on the one drum with the first winding on the other drum, is 80 led over the drum 1, which may consist of a grooved disc, so that between drum 2 and drum 3 a long run is obtained, the upper part of which is drawn over the distance between the drums 1 and 2 through a trough 85 5 containing melted wax, paraffine, stearine or the like or a mixture of these materials. As the wick can be very long, for instance 300 meters or even longer, and still changes 90 in length on its way through the first bath, the distance between the shafts of the two drums 2 and 3 is not a fixed one, but may be adjusted, as the frame 6, on which the drum 2 is mounted, is slidably arranged on the frame 7 of the apparatus and may be 95 adjusted by means of a screw with crank 8.

This arrangement has the advantage, that a slight horizontal sliding of the drum 2 suffices to stretch at once all windings of the wick in the desired way.

In order to prevent the wick, due to stretching from shifting within the candle wax or the like material and to ensure its remaining in the right place, an adjustable roller 9 is provided, which, by means of the 105 screw 10, is pressed toward the space be-

tween the drums 2 and 3, contrary to the winding of the wick, thus leading the wick in the right position. The roller 9 is, moreover, provided with grooves, in order to 5 keep the windings parallel.

As the wick 4, in the apparatus described by way of example, forms an endless band and is not drawn successively through a series of dies of increasing diameters, the 10 one placed behind the other in the manner as known hitherto, the device for holding the dies is constructed as indicated in Figs. 4 and 5, by way of example. Said device consists of tongs or a hinged clamp 11, in 15 which a die-disc 12, made of two parts, is fixed, which tongs or clamp can be fastened with the aid of a screw 13, provided with a winged-nut. The tongs are, or the clamp, is connected to a square bolt 14, which, by 20 means of screws 16, can be fixed into a socket 15, fitting around it. The socket 15 is in turn connected to the side of the trough 5.

The exchanging of the dies, without the wick being loosened, takes place in the following way:

When the wick has been led over its entire length through the trough 5, another clamp 11', with a die of the next larger size is slid in the socket 15, in front of the clamp 30 11. The clamp 11' is then shut and fastened in working order. As soon as the wick has passed round over its entire length, the first clamp 11 is opened and slid out of the socket 15, so that the die in the clamp 35 11', which is kept in readiness, immediately will come into operation. This latter die is then slid forward with its clamp 11' into the socket 15 in the place of the removed die 11. The exchanging of clamps with 40 calibers of increasing diameters is continued in this way until the candle material has attained the required thickness.

As aforesaid the die can also be constructed in another way and its fixing and adjustment may be varied in several manners.

The drums can be driven mechanically, for instance, with the aid of a pulley on the shaft of the drum 3.

To make sure that the windings on the drums 2 and 3 are laid quite close to each other, the two drums are mounted not exactly parallel but somewhat sloping with regard to each other.

The candle-material made in this way, is, after having attained the desired thickness, taken from the drums and cut into pieces of a certain length. These pieces are subsequently provided with a head at their ends in the known manner.

Claims:

1. A process for manufacturing candles, tapers and the like, consisting in leading an endless wick several times through a bath of wax, paraffine, stearine or the like or

mixtures of these materials, and through a die, and successively increasing the size of the die each time the wick has traveled its entire length through the latter, until the material has attained the desired thickness on the wick.

2. An apparatus for manufacturing candles, tapers and the like including a pan to contain a bath of wax or the like, a set of drums associated with said pan and adapted to support and move an endless wick through said pan, and a replaceable die associated with the pan and constructed to surround a wick, without severing the latter.

3. An apparatus as claimed in claim 2 in which the die includes a plurality of scraping members, and a hinged clamp for holding the scraping members in position.

4. An apparatus as claimed in claim 2 in which a socket is associated with the pan, and the die is slidably and removably mounted in the socket.

5. An apparatus for manufacturing candles, tapers and the like including a plurality of substantially superposed drums, a third drum spaced from the superposed drums, said drums being adapted to support an endless wick, a pan adapted to contain a bath of wax or the like, arranged between the superposed drums and the third drum to permit the passage of the endless wick through the pan, and a removable die associated with the pan and arranged around said wick.

6. An apparatus as claimed in claim 5 including means for adjusting the axis of one of the superposed drums relatively to the axis of the other one of the superposed drums.

7. An apparatus as claimed in claim 5 including an adjustable roller arranged to engage the wick as it passes from one of the superposed drums to the other one of the superposed drums.

8. An apparatus for manufacturing candles, tapers and the like, including a first lower drum, a second upper superposed drum, a third drum spaced from the first and second drums, said first and second drums having their axes arranged out of vertical alignment, means for moving one of the first mentioned drums relatively to the other first mentioned drum, a trough arranged between the first mentioned drums and the third drum and containing candle material, an endless wick wound about the first and second drums, passed over the third drum and passing through the trough, and a removable die surrounding said wick and removable from the latter without severing the wick.

In testimony whereof I affix my signature.

EUGEN BURIAN.
